UNITED STATES PATENT OFFICE

2,575,075

ADJUSTABLE ROTARY COUNTERBALANCE CRANK

John Fitz Eaton, Tulsa, Okla., assignor to Bethlehem Supply Company, a corporation of Delaware

Application February 24, 1949, Serial No. 73,023

13 Claims. (Cl. 74—591)

1.

This invention relates to improvements in counterbalance cranks for power shafts, and is particularly directed to an improvement in counterbalancing means for cranks for oil well drilling and pumping equipment of the specific type wherein weight elements are arranged to slide along a radially extending crank-arm, and means are provided to clamp the weight elements along the arm at varying distances from the center of rotation of the crank, whereby a variable amount of effective counterbalance is provided to offset the unbalance of the system due to the static pumping or drilling load.

A basic design of this type of counterbalance was disclosed in the patent to one Trout, numbered 1,588,784, and issued June 15, 1926. The counterbalances of the Trout design were so arranged that they could be positioned and fixed on the crank arm to balance the static pumping load and at the same time were so adapted that they could be moved to and fixed at the axis of rotation where their torque effect would have zero value. In the Trout patent arrangement the weights are attached to the crank-arm by means of bolts, the heads of which engage slots in the edges of the crank arm. The outer edges of the crank arm and the bottoms of the weights (when in their erect position) are machined to guide the weights along the crank arm, and to permit of relatively easy sliding when the crank arm is in a horizontal position and the weight to be adjusted is in its erect position. The usual procedure of weight adjustment in the Trout design is to rotate the crank shaft until the crank arm is in one of its two horizontal positions, and to temporarily lock the crank arm in this position by means of the power system's brake mechanism. Then by loosening the bolts holding the uppermost weight to the horizontal crank arm this weight may be moved to its new position by prying it with a bar—it is then re-bolted in its new position, the brake is released, and the operation is repeated for the then lowermost weight by rotating the crankshaft 180° to bring the crank arm into its other horizontal position, whereby the second weight now on top may be adjusted. In the larger sizes of modern pumping units the counterbalance weights required may be of the order of 6000 pounds each, and the moving thereof manually with a pry-bar in the hands of a workman forced to stand on some portion of the apparatus in order to work the bar is attended by an element of danger, and is arduous and time consuming. My invention therefor lies in an improvement for the Trout

2.

type of counterbalance crank for oil well drilling and pumping equipment designed to reduce the time and labor required to rebalance the unit, and to reduce to a minimum the danger of injury in so doing.

It is therefore the primary object of my invention to construct a counterbalance crank arm for oil well drilling and pumping equipment having the weights thereof adapted to be slidably adjustable along opposite edges thereof in the plane of revolution, and wherein the said adjustment is readily and efficiently made to both said weights when the crank arm is in either one of its two substantially horizontal positions.

It is a further object of my invention to provide a counterbalance crank arm having support rails thereon for the support of slidably adjustable weights so arranged that whether the weights to be adjusted are in an erect or in a pendant position they may be equally readily and efficiently moved on, adjusted to, and clamped to their respective support rail.

It is another object of my invention to have the support rails of my improved counterbalance crank in its preferred form to be removably attached to the crank arm thereof, and to have the support rails thereof comprise flat rectangular bars disposed in parallel spaced relation along each edge of the said crank arm, both said crank arm and said support rails lying flatwise with respect to the plane of revolution of the crank arm, whereby the bearing means of the weights engage both edges of their respective support rails, and the weight clamp means engage both sides thereof.

It is another object of my invention to provide a crank-operated rack-and-pinion means for readily and efficiently controlling the positioning of the weights along the support rails of my improved counterbalance crank.

It is another object of my invention to so design the clamping elements that normally hold my counterbalance weights in operating position that when in the loosened condition for adjusting the weights, the clamping elements are freed of undue clamping friction by reason of an inherent elasticity established in the structural design of the assembled weights.

It is still another object of my invention to provide a novel dual clamping means for securing my improved counterbalance crank unit upon its driving shaft and for clamping the support rails thereof to the crank arm.

Further objects and advantages will be apparent from the following description wherein de-

tails of design and operation will be given in full with reference to the accompanying drawings illustrating the preferred embodiment of my invention, and wherein similar reference numerals designate similar parts throughout the several views.

Fig. 1 is a front elevation of a counterbalance crank unit incorporating the preferred form of my invention. The view comprises partial sections, and is shown with the front half of the upper weight removed to better disclose detail structure.

Fig. 2 is a view looking upward at the bottom of the unit as shown in Fig. 1.

Fig. 3 is an end elevation of the left end of the unit as shown in Fig. 1, having a partial section thereof.

Fig. 4 is an elevation of the right end of the unit as shown in Fig. 1, having a partial section thereof, and,

Fig. 5 is a sectional view taken along the line 5—5 of Fig. 1 as seen in the direction of the arrows 5—5.

Referring now to the drawings, and more particularly to Fig. 1, the numeral 10 designates the complete ensemble of a counterbalance crank unit embodying the preferred form of my invention.

The counterbalance crank unit 10 comprises two main sub-assemblies—the crank arm assembly 11, and the two counterbalance weight assemblies 12.

The crank arm assembly 11 is comprised of the crank arm 13, and the support rail assemblies 14.

The crank arm 13 is preferably a gray-iron casting with the conventional finished keyed shaft bore 15, and the finished keyed wrist-pin holes 16. The shaft bore 15 is adapted to be secured to a power shaft (not shown) normally rotated by a suitable source of power. The shaft bore 15 may be surrounded with a solid-hub (not shown) and pressed on the power shaft in a well known manner, or it may have a split-hub 17 as shown in Fig. 1 extending to the outer end of the crank arm 13 and be clamped on the power shaft as hereinafter described. The wrist pin holes 16 (four in number as shown in Fig. 1) permit the attachment of the wrist pin bearing (not shown) at various distances toward or away from the crank shaft bore 15 depending upon the desired pumping stroke-length. Legend numerals 18 may be provided opposite each wrist pin hole 16 indicating the pumping stroke-length provided by using the respective holes for the wrist pin bearing. At both ends of the crank arm 13 and at opposite edges thereof are cored bolt-holes 19 to be hereinafter referred to in more detail. Extending substantially full-length on each side of the crank arm 13 are outwardly extending serrated flanges 20—the serrations 21 of which are preferably a form of gear teeth the purpose of which will be hereinafter more fully described.

The support rail assemblies 14 are each a unitary welded structure comprising a smooth finished steel rail bar 22 welded at each end thereof to hanger castings 23. The rail bars 22 are preferably of rolled steel, rectangular in cross-section, and are preferably jig-welded as at 24 and 25 into slots 26 cast in the hanger castings 23. The hanger castings 23 are provided with a cored bolt slot 27 cast therein. The bolt slots 27 are provided on their inner upper surface with recesses 28 to receive the bolt heads and prevent them from turning when manipulating the nuts thereon. The inner end of this bolt slot 27 is provided at its

outer semi-circular edge with an integral conical projection 29 designed to project into a matching conical recess 30 formed at the outer ends of the cored bolt holes 19 in the crank arm 13 (see Fig. 3). The purpose of these conical projections fitting into a matching recess in the crank arm is to position the rail assemblies 14 on the crank arm 13 and to prevent lateral displacements thereof when the support rail assemblies 14 are fastened

in place on the crank arm 13 by the fastening means 31 and 32 (see Fig. 1). The fastening means 31 function to fasten the outer ends of the rail assemblies 14 to the outer end of the crank arm 13 and they comprise the bolts 33 extending through the cored bolt slots 27 in the hanger castings 23, and through the cored bolt-holes 19 in the outer end of the crank arm 13. The fastening means 31 are completed by the nuts 34 and lock washers 35. The fastening means 32 (see Figs. 1 and 4) performs a dual function—it fastens the inner ends of the rail assemblies 14 to the inner end of the crank arm 13 and it acts to clamp the crank arm 13 to its power shaft (not shown) by its clamping action on the shaft bore 15. The fastening means 32 comprises the two bolts 36 and 37 having right and left hand threads respectively, the turnbuckle nut 38, and the lock nuts 39 and 40. The turnbuckle nut 38, and the lock nuts 39 and 40 are suitably tapped for the bolts 36 and 37.

It is obvious of course that when a pressed-on type of crank arm is used, as noted hereinabove, that the fastening means 31 may be used at the inner ends of the rail assemblies to replace the turnbuckle type 32 not then necessary.

With the split type of crank arm 13 as shown in Fig. 1 the rail assemblies 14 are assembled to the crank arm 13 by first placing the bolts 33, 36 and 37 in their respective ends of the rail assemblies 14 minus their nuts. The rail assemblies are then simultaneously assembled to the crank arm 13 by entering the bolts through their respective bolt holes 19, until the nuts 39 and 40 may be threaded upon the bolts 36 and 37, and the turnbuckle nut 38 may engage the bolts 36 and 37 simultaneously for the purpose, well known to mechanics, of drawing the bolts and their associated parts together to a simultaneous seating upon the crank arm 13. The nuts 34 and lock washers 35 are then placed on the bolts 33 and tightened to complete the assembly.

The two counterbalance weight assemblies 12 are each comprised of the two half-weights 41, bolted together by means of an outer pad clamp bolt 42 and four rail clamp bolts 43 each provided with nuts 44 and washers 45; weight rollers 46 mounted on said rail clamp bolts 43; and, pinion assembly 47 (see Fig. 5).

The half-weights 41 are identical and are preferably made of cast iron. Each half-weight 41 is provided with cored bolt hole 48 for the pad clamp bolt 42 and the rail clamp bolts 43. The outer end of each cored bolt hole 48 is provided with the recesses 49 and 50 (see Fig. 5). The recesses 49 are adapted to fit the head of the bolts 42 and 43 to prevent their turning when being manipulated with a wrench, and the recesses 50 are adapted to provide clearance for the use of a socket wrench (not shown) and at the same time place the bolt heads and nuts below the face surfaces of the half-weights 41. In the case of the half-weight 41 comprising in its assembly the nuts 44 and the washers 45 the washers cover the recesses 49 and permit the nuts 44 to be rotated with respect to their bolts. On

the inner side of each half-weight 41 on the horizontal center line of the pad clamp bolt 42 and transversely adjacent on each side of its vertical center line are the raised spacing pads 51 having the faces 52 (see Figs. 1 and 3) which are in mutual engagement when the half-weights 41 are bolted together by the pad clamp bolt 42. Also on the inner side of each half-weight 41 on the vertical center lines of the rail clamp bolts 43 and spaced therebetween in each case are the rail clamp pads 53 having faces 54 (see Figs. 1 and 5) which are in parallel spaced relation one with another when the half-weights 41 are bolted together by the pad clamp bolt 42. When assembled in the complete counterbalance crank unit 10 and ready for use the faces 54 of the opposed rail clamp pads 53 are in intimate engagement with opposite faces of their adjacent intervening rail bar 22 by reason of the clamping action of the four rail clamp bolts 43 in their tightened condition, the intervening distance then existing between the faces 54 is the actual thickness of the rail bar 22. However, when the bolts 43 are loosened it is desirable that a slight clearance automatically exist between the rail bar and the faces 54 in order that the weights may be readily moved without undue frictional restraint. To accomplish this desirable feature the difference in height between the faces 52 of the spacing pads 51 and the faces 54 of the rail clamp pads 53 is so adapted that when in its assembled position with the pad clamp bolt 42 tightened and free of other tension by reason of the rail clamp bolts 43 being loosened the spaced distance between the faces 54 is slightly greater than when they are drawn into engagement with the rail bar 22 by the tightening of the bolts 43. This untightened clearance may be of the order of one-thirty-second of an inch for each side of the bar—a clearance well within the operable elastic limits of the parts strained when the bolts 43 are tightened.

In addition to serving as a clamping means the bolts 43 also serve as bearings for the weight rollers 46. The rollers 46 are preferably made of bronze and the bolts made of stainless steel to avoid rusting. The rollers 46 are adapted to rotate at all times with adequate clearance endwise with respect to the depressed surfaces 55 (see Fig. 5) of the half-weights 41. Recesses 56 (see Fig. 1) in the half-weights 41 provide adequate diametral clearances about the outer ones of the rollers 46.

The pinion assembly 47 (see Fig. 5) comprises the pinion 57, bushing bearings 58, and snap spring retaining rings 59.

The pinion 57 is preferably of cast steel having a central portion with cast gear teeth 60, outwardly extending shaft bearing portions 61, and shaft end portions 62 adapted for engagement with a suitable hand crank socket wrench (not shown). Between the bearing portions 61 and the end portions 62 the shaft extensions are adapted with grooves 63 for snap spring retaining rings 59. For mounting the pinion assembly 47 the half-weights 41 are provided with the cylindrical recesses 64 adjacent the inner edge thereof on its vertical center line, and each recess 64 is further provided with an inner shouldered recess 65 (see Figs. 1 and 5). The inner recesses 65 are adapted to be slightly larger in diameter than the outside diameter of the cast gear teeth 60 whereby the pinion 57 may be inserted or withdrawn therethrough (see Fig. 1). The recesses 64 are adapted to receive the bush-

ing bearings 58, and these bearings 58 are retained in their supporting position upon the pinion 57 by reason of the snap spring retaining rings 59 and in the recesses 64 by reason of the shouldered recesses 65. By referring to Fig. 1 it is seen that the pinion assemblies 47 when placed in their respective positions in the supporting recesses 64 and 65 bring their central toothed portions 60 into operating engagement with the adjacent gear teeth 21 of the respective outwardly extending serrated flanges 20 of the crank arm 13.

Suitably placed on the outer face of each of the half-weights 41 adjacent the pinion assembly recess 64 thereof is provided a position index boss 66. The index boss 66 is intended to cooperate with a respective scale 67 graduated along the adjacent serrated flanges 20. The scale 67 may be marked with legend numbers 68 having known counterbalancing values which may be chosen selectively for use in adjusting the counterbalance weight assemblies 12 to their desired position.

Each of the half-weights 41 are provided with a cored hole 69 on the vertical center line thereof adjacent the pad clamp bolts 42. This cored hole is provided for lifting the weights 12, and assembled unit 10 if and when necessary.

The counterbalance weight assemblies 12 are readily assembled to or dismounted from the crank arm assembly 11 as follows:

With the crank arm assembled 11 as hereinbefore described and placed in a horizontal position, one of the counterbalance weight assemblies 12 complete except for the two inner rail clamp bolts 43 and the pinion assembly 47 may be lifted, using the lifting holes 69, and then set in position on the uppermost rail bar 22 about midway of its ends. Bottom weight rollers 46 may then be inserted between the two half-weights 41, and between the rail bar 22 and the upper serrated flange 20 of the crank arm. The rollers 46 are inserted one at each end of the weights and each may be pushed inward to alignment position with the lower cored bolt holes 48. In order to prevent the rollers 46 going past the holes 48, lugs 70 are provided cast integral with the half-weights 41 adjacent each lower bolt hole 48 (see Fig. 1). The lower rail clamp bolts 43 may next be inserted from the back face of the counterbalance weight assembly 12 through the rollers 46, and all the rail clamp bolts 43 with their associated nuts 44 and washers 45 may be tightened in place. The assembly of this counterbalance weight assembly 12 to the crank arm assembly 11 is completed by installing the pinion assembly 47 as hereinbefore described. The crank arm assembly 11 together with its first counterbalance weight assembly 12 clamped thereto is then revolved 180° about its shaft bore 15, and the second counterbalance weight assembly 12 is assembled thereto in the manner just described for the first one.

The operation of adjusting the weights to a desired position when in the field and in use will now be described. The counterbalance crank unit 10 is rotated to have its crank arm 13 in either one of its two horizontal positions, as may be most convenient, and is so locked by means of the power systems brake throughout the whole adjusting operation. Both weight assemblies 12 may be adjusted from this one locked position by the operator standing on the ground, facing the crank, and clear of the unit while moving the weight assemblies 12 to their new positions;

When the rail clamp bolts 43 are loosened the rail clamp pads 53 free themselves from intimate contact with the rail bars 22, as hereinbefore described, thereby eliminating friction at these surfaces. The operator using a hand crank socket wrench applied to the squared exposed end portion 62 of the pinion 57 is able to move the weights 12 readily, and under constant control, by reason of the crank driven pinion-and-rack mechanism in combination with the rollers 46 supporting the weights. The ease of operation together with the ability to do all adjusting with one position of the crank arm reduces the time and labor required, as well as making a safer operation. The adjustments made, and the clamp bolts retightened, the counterbalance crank unit 10 is again ready for use.

It may be further noted that I have provided rack teeth 21 the full length of the crank arm 13 although the pinion normally moves only in the middle section of the rack in the course of transferring the weight assemblies 12 from maximum to minimum effective position. In the event the pinion 57 is inoperative due to breakage, excessive rusting, and et cetera, it may be removed and the weight assemblies 12 moved by means of a bar in conjunction with the rack teeth 21 which will serve as a fulcrum for the end of the bar. In conjunction with such emergency use of a bar I provide a prying space 71 (see Fig. 1) between the hanger castings 23 and the weights 12 in order that the weights may be pried away from an extreme end position, and the rack teeth near the ends of the crank arms 13 may then be used as fulcrums for the pry bar, to thus move the weights 12 toward the middle of the crank arm 13.

I claim:

1. In a counterbalancing device for power shafts, the combination of a radial arm adapted to be mounted on a shaft and provided with serrated edges along both sides thereof in the plane of revolution, rail bars spaced from parallel to and located in substantially vertical alignment with said serrated edges, counterweights supported on and adapted for slidable engagement with each of said rail bars in both an erect and a pendant relationship with respect to said radial arm, means for clamping said counterweights immovably with respect to said rail bars, and crank operable pinion means mounted in each of said counterweights in operable engagement with their respective adjacent serrated edge.

2. In a counterbalancing device for power shafts, the combination of a radial arm adapted to be mounted on a shaft and provided with serrated edges along both sides thereof in the plane of revolution, rail bars spaced from parallel to and located in substantially vertical alignment with said serrated edges, counterweights supported on and adapted for slidable engagement with each of said rail bars in both an erect and a pendant relationship with respect to said radial arm, means for clamping said counterweights immovably with respect to said rail bars, means effective to permit free slidability and secure clamping of the counterweights when the said clamping means are respectively loosened or tightened, and crank operable pinion means mounted in each of said counterweights in operable engagement with their respective adjacent serrated edge.

3. In a counterbalancing device for power shafts, the combination of a radial arm adapted to be mounted on a shaft and provided with ser-

rated edges along both sides thereof in the plane of rotation, rail bars spaced from parallel to and located in substantially vertical alignment with said serrated edges, means for attaching said rail bars to the radial arm, counterweights supported on and adapted for slidable engagement with said rail bars in both an erect and a pendant relationship with respect to said radial arm, means for clamping said counterweights immovably with respect to said rail bars, and crank operable pinion means mounted in each of said counterweights in operable engagement with their respective adjacent serrated edge.

4. In a counterbalancing device for power shafts, the combination of a radial arm adapted to be mounted on a shaft and provided with serrated edges along both sides thereof in the plane of revolution, rail bars spaced from parallel to and located in substantially vertical alignment with said serrated edges, two-part counterweights having their outward portions in united mutual facial engagement comprising fastening means for maintaining said facial engagement, crank operable pinion means mounted in each of said counterweights in operable engagement with their respective adjacent serrated edge, and having bearing means in each of said counterweights engaging the inner and outer longitudinal edges of their respective said rail bars for slidable adjustment of the counterweights thereon whereby said adjustment may be made in both an erect and a pendant relationship of said counterweights with respect to said radial arm, and means for clamping inner surfaces of said counterweights on the respective opposed parallel faces of the said rail bars.

5. In a counterbalancing device for power shafts, the combination of a radial arm adapted to be mounted on a shaft and provided with serrated edges along both sides thereof in the plane of revolution, rail bars spaced from parallel to and located in substantially vertical alignment with said serrated edges, two-part counterweights having their outward portions in united mutual facial engagement comprising fastening means for maintaining said facial engagement, and having bearing means in each of said counterweights engaging the inner and outer longitudinal edges of their respective said rail bars for slidable adjustment of the counterweights thereon whereby said adjustment may be made in both an erect and a pendant relationship of said counterweights with respect to said radial arm, means for clamping inner surfaces of said counterweights on the respective opposed parallel faces of the said rail bars, means effective to permit free slidability and secure clamping of the counterweights when the said clamping means are respectively loosened and tightened, and crank operable pinion means mounted in each of said counterweights in operable engagement with their respective adjacent serrated edges whereby said counterweights may be manually adjusted when the radial arm is in a substantially horizontal position.

6. A counterbalance crank arm for power shafts, comprising a radial arm adapted to be mounted on a power shaft and to support a wrist pin and provided with serrated edges along both sides thereof in the plane of rotation, rail bars spaced from parallel to and located in substantially vertical alignment with said serrated edges, two-part counterweights having their outward portions in united facial engagement comprising fastening means for maintaining said

facial engagement, crank operable pinion means mounted in each of said counterweights in operable engagement with their respective adjacent serrated edge, and having roller bearing means mounted in each of said counterweights engaging the inner and outer longitudinal edges of said rail bars for slideable adjustment of the counterweights thereon whereby said adjustment may be made in both an erect and a pendant relationship with respect to said radial arm, and comprising operable fastening means effective for clamping inner surfaces of said counterweights on the respective opposed parallel faces of the said rail bars and for supporting said roller bearings in their operable relation whether said counterweights are in clamped or unclamped relationship with said rail bars.

7. A counterbalance crank arm for power shafts, comprising a radial arm adapted to be mounted on a power shaft and to support a wrist pin and provided with serrated edges along both sides thereof in the plane of rotation, rail bars spaced from parallel to and located in substantially vertical alignment with said serrated edges, two-part counterweights having their outward portions in united facial engagement comprising fastening means for maintaining said facial engagement, crank operable pinion means mounted in each of said counterweights in operable engagement with their respective adjacent serrated edge, and having roller bearing means mounted in each of said counterweights engaging the inner and outer longitudinal edges of said rail bars for slideable adjustment of the counterweights thereon whereby said adjustment may be made in both an erect and a pendant relationship with respect to said radial arm, and comprising operable fastening means effective for clamping inner surfaces of said counterweights on the respective opposed parallel faces of the said rail bars and for supporting said roller bearings in their operable relation whether said counterweights are in clamped or unclamped relationship with said rail bars, and means effective to permit free slidability and secure clamping of the counterweights when the said clamping means are respectively loosened or tightened.

8. A counterbalance crank arm for power shafts, comprising a radial arm adapted to be mounted on a power shaft and to support a wrist pin and provided with serrated edges along both sides thereof in the plane of revolution, rail bars spaced from parallel to and located in substantially vertical alignment with said serrated edges, two-part counterweights having their outward portions in united facial engagement comprising fastening means for maintaining said facial engagement, and having roller bearing means mounted in each of said counterweights engaging the inner and outer longitudinal edges of said rail bars for slideable adjustment of the counterweights thereon whereby said adjustment may be made in both an erect and a pendant relationship with respect to said radial arm, and comprising operable fastening means effective for clamping inner surfaces of said counterweights on the respective opposed parallel faces of the said rail bars and for supporting said roller bearings in their operable relation whether said counterweights are in clamped or unclamped relationship with said rail bars, means effective to permit free slidability and secure clamping of the counterweights when the said clamping means are respectively loosened or tightened, and crank operable pinion means mounted in

each of said counterweights in operable engagement with their respective adjacent serrated edges whereby said counterweights may be manually adjusted when the radial arm is in a substantially horizontal position.

5 9. A counterbalance crank arm for power shafts, comprising a radial arm adapted to be mounted on a power shaft and to support a wrist pin and provided with serrated edges along both 10 sides thereof in the plane of revolution having attachment abutments at each end thereof, rail bars spaced from parallel to and located in substantially vertical alignment with said serrated edges comprising end attachment means 15 adapted for fixed engagement with said abutments, detachable fastening means for maintaining said fixed engagement, counterweights supported on and adapted for slideable engagement with said rail bars in both an erect and a pendant relationship with respect to said radial arm, means for clamping said counterweights immovably with respect to said rail bars, and crank operable pinion means mounted in each of said counterweights in operable engagement 20 with their respective adjacent serrated edge.

10 10. A counterbalance crank arm for power shafts, comprising a radial arm adapted to be mounted on a power shaft and to support a wrist pin and provided with serrated edges along both 30 sides thereof in the plane of revolution having attachment abutments at each end thereof, rail bars spaced from parallel to and located in substantially vertical alignment with said serrated edges comprising end attachment means adapted 35 for fixed engagement with said abutments, detachable fastening means for maintaining said fixed engagement, counterweights supported on and adapted for slideable engagement with said rail bars in both an erect and a pendant relationship with respect to said radial arm, means for clamping said counterweights immovably with respect to said rail bars, crank operable pinion means mounted in each of said counterweights in operable engagement with their 40 respective adjacent serrated edge, and means effective to permit free slidability and secure clamping of the counterweights when the clamping means are respectively loosened or tightened.

11 11. A counterbalance crank arm for power shafts, comprising a radial arm adapted to be mounted on a power shaft and to support a wrist pin and provided with serrated edges along both 50 sides thereof in the plane of revolution having attachment abutments at each end thereof, rail bars spaced from parallel to and located in substantially vertical alignment with said serrated edges comprising end attachment means adapted for fixed engagement with said abutments, detachable fastening means for maintaining said fixed engagement, counterweights supported on and adapted for slideable engagement with said rail bars in both an erect and a pendant relationship with respect to said radial arm, means for clamping said counterweights immovably with respect to said rail bars, crank 55 operable pinion means mounted in each of said counterweights in operable engagement with their respective adjacent serrated edge, and fastening means effective to simultaneously fix the radial arm to its shaft and to fix one end of each of said rail bars to said radial arm.

60 12. A counterbalance crank arm for power shafts, comprising a radial arm adapted to be mounted on a power shaft and to support a 65 wrist pin and provided with serrated edges along

11

both sides thereof in the plane of revolution having attachment abutments at each end thereof, rail bars spaced from parallel to and located in substantially vertical alignment with said serrated edges comprising end attachment means adapted for fixed engagement with said abutments, detachable fastening means for maintaining said fixed engagement, counterweights supported on and adapted for slidable engagement with said rail bars in both an erect and a pendant relationship with respect to said radial arm, means for clamping said counterweights immovably with respect to said rail bars, means effective to permit free slidability and secure clamping of the counterweights when the clamping means are respectively loosened or tightened, and crank operable pinion means mounted in each of said counterweights in operable engagement with their respective adjacent serrated edges whereby said counterweights may be manually adjusted when the radial arm is in a substantially horizontal position.

13. A counterbalance crank arm for power shafts, comprising a radial arm adapted to be mounted on a power shaft and to support a wrist pin and provided with serrated edges along both sides thereof in the plane of revolution having attachment abutments at each end thereof, rail bars spaced from parallel to and located substantially vertical alignment with said serrated edges comprising end attachment means adapted for fixed engagement with said abutments, detachable fastening means for maintaining said fixed engagement, two-part counterweights having their outward portions in united mutual 35 facial engagement comprising fastening means

12

for maintaining said facial engagement, and having bearing means in each of said counterweights engaging the inner and outer longitudinal edges of their respective said rail bars for slidable adjustment of the counterweights thereon whereby said adjustment may be made in both an erect and a pendant relationship of said counterweights with respect to said radial arm, means for clamping inner surfaces of said counterweights on the respective opposed parallel faces of the said rail bars, means effective to permit free slidability and secure clamping of the counterweights when the said clamping means are respectively loosened and tightened, crank operable pinion means mounted in each of said counterweights in operable engagement with their respective adjacent serrated edges whereby said counterweights may be manually adjusted when the radial arm is in a substantially horizontal position, and fastening means effective to simultaneously fix the radial arm to its shaft and to fix one end of each of said rail bars to said radial arm.
